WARPING APPARATUS

John Ellsworth Fite, Philadelphia, Pa.

Application April 7, 1932, Serial No. 603,851

3 Claims. (Cl. 28—35)

This invention relates to an apparatus and method for warping uncovered strands or threads of rubber. The object of the invention is to wind uncovered rubber strands or threads on a warp beam or spool for use in a loom without placing the rubber threads under any tension whatsoever, in order that the rubber threads may be fed to the loom, such as narrow fabric or tape loom adapted for producing elastic webbing or fabric, 10 in a fully contracted normal state.

Rubber threads as they come from extruding or other forming machines are wound on a primary spool in superposed layers, by what is generally known as straight winding, that is, the 15 threads in each and all layers are substantially parallel circumferentially of the spool, consequently the threads in one layer frequently are pulled, pressed, or jammed down between the threads of the underlying layer, as a result, for 20 example, of unavoidable variations between the linear speed of production and the linear speed of winding of the individual threads, therefore, as the threads are being drawn off the primary spool the threads of the one layer that are jammed 25 in among the threads of the underlying layer produces a spasmodic pull or tension on the thread being withdrawn, which produces an uneven tension on the thread which makes it impossible to rewind the thread on a warp beam with 30 out having any tension in the thread. The total absence of tension in the threads is essential when uncovered rubber threads are wound on a beam to be used in a loom for making elastic fabric.

The method of the present invention contemplates the unwinding of the threads from the straight wound primary spools, as received from the extruding machine, and to rewind the threads on other secondary carrying spools, by what is generally known as the "universal" or "cross 35 wind" method, to prevent the threads of one layer from sticking to the threads of an underlying layer.

A plurality of these secondary cross wound spools are subsequently placed in a suitable supporting frame, and the cross wound rubber threads are fed off the secondary spools at a uniform predetermined linear speed; and at the same time the plurality of threads are rewound on the warp beam, by the old straight wind method, at the same linear speed at which the threads 50 are fed from the cross wound spools.

As a result of this method of rewinding the threads on the warp beam, the threads on the beam will not be under any tension whatsoever even though the straight wound method is used

in rewinding the threads on the warp beam, consequently the threads can be withdrawn from the warp beam without sticking together and as a result thereof the rubber warp threads pass from the warp beam to the tensioning device of the 60 loom without tension, and the tensioning device of the loom can consequently place all the warps uniformly under any desired tension as they pass into the shedding mechanism of the loom.

Fig. 1 of the accompanying drawings is a plan view of the machine which receives the straight wound primary spools, as they come from the thread-forming machine, and by which the threads are cross wound on the secondary spools; 65

Fig. 2 is a sectional elevation taken on the line 70 2—2, Fig. 1;

Fig. 3 is a plan view of the rewinding apparatus wherein the threads are rewound from the cross wound secondary spools onto the warp beam under the straight wind method but without tension; 75

Fig. 4 is a side elevation of the apparatus shown in Fig. 3; and

Fig. 5 is a sectional elevation taken on the line 5—5, Fig. 3.

The apparatus shown in Figs. 1 and 2 comprises 80 a framework 1 in which is rotatably mounted a pair of drums 2 and 3 respectively, and which are exactly the same diameter, the drums 2 and 3 being secured to shafts 4 and 5 respectively which are rotatably mounted in the framework 1. 85

Rotatably mounted in suitable bearings carried by or formed in the framework 1 is a cam shaft 7 on which is secured a sprocket wheel 8, around which passes a drive chain 9 which also passes around sprocket wheels 10 and 11 on the shafts 90 4 and 5 respectively, the shaft 5 being provided with tight and loose pulleys 12 and 13 respectively by which the machine is driven.

Pivotedly mounted to the frame 1 at the points 14 and 15 are frames 16 and 17 respectively, these 95 frames being in alignment with each other and with the drums 2 and 3 as shown in Fig. 1.

The frame 16 is adapted to receive the straight wound spools x as they come from the thread-forming machine, the drum 2 fitting between the 100 flanges of the spool x so that the outermost layer of the rubber threads r bears against the peripheral surface of the drum 2, weights 18 being provided on the frame 16 to maintain a driving contact between the outer layer of rubber threads r 105 and the peripheral surface of the drum 2.

The frame 17 carries the spool x^1 on which the rubber threads r are adapted to be cross wound, the outer layer of the rubber threads bearing 110 against the peripheral surface of the drum 3.

which is disposed intermediate the end flanges of the spool x^1 , weights 19 being provided on the frame 17 to maintain a driving contact between the rubber threads r on the spool x^1 and the peripheral surface of the drum 3.

The drums 2 and 3, being of the same diameter and driven at exactly the same speed with the outermost layer of rubber threads r in each instance bearing against the peripheral surfaces of the drums respectively, causes the threads to be forcibly unwound from the spool x and rewound on the spool x^1 at exactly the same lineal speed.

The cross winding of the threads r on the spool x^1 is accomplished by a traversing thread guide 20 which is adapted to reciprocate transversely of the machine at a fairly high rate of speed. Such relatively rapid reciprocation of the thread guide 20 produces a shaking action of the thread r as it comes from the spool x which loosens the thread in such places where it has become jammed down between the threads of the underlying layer, thus preventing the above mentioned spasmodic tension from being applied to the thread r as it is unwound from the spool x , which permits the thread to run through the traversing eye or guide 20 without any tension whatsoever, the traversing thread guide at the same time winding the thread r on the spool x^1 in cross wound superposed layers, which prevents any pulling of the threads of one layer between the threads of the underlying layer.

The traversing guide 20 is carried by a laterally reciprocable plate or frame 21 to which is pivotally attached one end of a lever 22, the opposite end of which is pivotally mounted at 23 to a cross bar 24 of the frame 1.

The lever 22 is slotted intermediate its ends for the reception of a pin or stud 25 projecting upwardly from a horizontally disposed bar 26, which is secured to a rod 27 that is slidably mounted in the side frames 1, 1 of the machine.

The bar 26 is provided with a downwardly extending pin or stud 28 which rides in a cam groove 29 of the cam wheel 30 carried by and rotatable with the cam shaft 7.

After winding on the machine shown in Figs. 1 and 2, the spools x^1 are placed in frames 31 which are pivotally mounted at 32 to the framework 33 of the warping machine, the cross wound threads r on the spools x^1 bearing on the peripheral surfaces of drums 34, 34 which are secured to the shafts 35 that are rotatably mounted in the frame 33.

Each shaft 35 is provided with a sprocket wheel 36 around which passes a drive chain 37 for driving all the drums 34 at exactly the same rate of speed, it being noted that all the said drums 34 are of exactly the same diameter.

Each of the frames 31 is weighted, as at 38, for maintaining uniform driving contact between the threads r of the outer layer on the spools x^1 with the peripheral surfaces of the drums 34 respectively so that all the threads r will be forcibly fed from the spools x^1 at exactly the same rate of lineal speed, the threads r passing from the drums 34 through suitable thread guides 39 to a comb or reed 40 carried by the warp winding machine 41 which is provided with a drum 42 of exactly the same diameter as the drums 34 above referred to.

The machine 41 is provided with a frame 43 which is pivotally mounted at 44 to the frame 41 and adapted to receive the warp spool w . From the pivoted frame 43 is suspended a weight or weights 55 that maintain a uniform driving contact between the threads r as they pass on to the

warp spool or beam w and the peripheral surface of the drum 42, which is disposed intermediate the end flanges of the warp spool w .

The drum 42 is secured to a shaft 45 rotatably mounted in the frame of the machine 41 and provided with tight and loose pulleys 46 and 47 by which the warping machine is driven, the shaft 45 being provided with a sprocket wheel 48 around which passes a chain 49 which also passes around a sprocket 50 secured on one of the shafts 35 which are rotatably mounted in the frame 33, so that the rewinding drum 42 and all the unwinding drums 34, all of which are of the same diameter, are driven at exactly the same peripheral speed, consequently the threads r are forcibly fed or delivered from the spools x^1 at a definite predetermined lineal speed and are forcibly wound on the warp beam w at exactly the same lineal speed, which prevents the production of any tension whatsoever in the threads r as they are wound on to the warp beam w .

I claim:

1. In an apparatus for warping rubber threads in a substantially normally contracted state the combination of a pair of relatively spaced wheels of equal diameter, means for rotating the wheels at substantially equal speeds, means adjacent said wheels for supporting cylindrical packages of rubber thread in frictional contact with the peripheral surfaces of the said wheels respectively, whereby the thread of one of said packages will be unwound therefrom at a predetermined linear speed substantially equal to the peripheral speed of the contacting wheel and the thread being fed therefrom will extend to and be wound on the other of said packages at substantially the same rate of linear speed by peripheral contact of the last said package with the peripheral surface of the second of said wheels.

2. In an apparatus for warping rubber threads in a substantially normally contracted state the combination of a pair of relatively spaced wheels, means for rotating the wheels at substantially equal peripheral speeds, means adjacent said wheels for supporting cylindrical packages of rubber thread in frictional contact with the peripheral surfaces of the said wheels respectively, whereby the thread of one of said packages will be unwound therefrom at a predetermined linear speed substantially equal to the peripheral speed of the contacting wheel and the thread being fed therefrom will extend to and be wound on the other of said packages at substantially the same rate of linear speed by peripheral contact of the last said package with the peripheral surface of the second of said wheels leaving the portion of the thread intermediate the packages in a normally contracted state, and means for agitating the said intermediate portion of the thread to release the thread from retarding influences at the point of delivery from the package being unwound.

3. In an apparatus for warping rubber threads in a substantially normally contracted state the combination of a pair of relatively spaced wheels, means for rotating the wheels at substantially equal peripheral speeds, means adjacent said wheels for supporting cylindrical packages of rubber thread in frictional contact with the peripheral surfaces of the said wheels respectively, whereby the thread of one of said packages will be unwound therefrom at a predetermined linear speed substantially equal to the peripheral speed of the contacting wheel and the thread being fed

therefrom will extend to and be wound on the other of said packages at substantially the same rate of linear speed by peripheral contact of the last said package with the peripheral surface of the second of said wheels leaving the portion of the thread intermediate the packages in a normally contracted state, and means for laterally reciprocating the said intermediate portion of the

thread relative to its normal line of travel between said packages for releasing the thread from retarding influences at the point of delivery from the one package and to lay the thread in a normally contracted state in superposed cross-wound layers on the other of said packages.
